UNITED STATES PATENT OFFICE.

DAVID BLACK, OF EDWARDSVILLE, ILLINOIS.

AEROPLANE.

1,016,929.

Specification of Letters Patent. Patented Feb. 13, 1912.

Application filed February 9, 1911. Serial No. 607,462.

To all whom it may concern:

Be it known that I, DAVID BLACK, a citizen of the United States, residing at Edwardsville, in the county of Madison and State of Illinois, have invented certain new and useful Improvements in Aeroplanes, of which the following is a specification.

My invention relates to aeroplanes, and the invention consists in certain novel and original features of construction and combinations of parts not heretofore known or used so far as I am aware and which, as I believe, constitute a decided step in advance in this art, all substantially as shown and described and particularly pointed out in the claims.

In the accompanying drawings, Figure 1 is a perspective view of the invention, and Fig. 2 is a plan view thereof. Fig. 3 is a perspective view of a sectional detail enlarged and particularly showing my novel method of coupling together parts of the frame. Fig. 4 is a front elevation and Fig. 5 is a perspective view of the central or seat portion of machine with modifications hereinafter described, and Fig. 6 is a detail in section of a portion of the main frame and of a plane pivot connection therewith. Fig. 7 is a side elevation of the machine, and Fig. 8 is a perspective view of the tail and rudder. Fig. 9 shows details relating to the seat supporting tubes, at the rear. Fig. 10 is a perspective view of one of the controlling springs for the planes.

As thus shown the machine comprises a relatively light rigid main frame consisting of uprights 2 at each side connected by a bowed cross-piece 3 top and bottom, and with the bow indicated by b extending to the front of said frame and serving as a guard and as a bracing connection between the top and bottom of the frame, thus making the frame materially more rigid and with greater strength than it could have if the said bows were omitted. In fact by means of these bows I can use lighter material in the frame as a whole than would be possible without them. The material used for these frames may be of any suitable kind and of any needed strength, and the said frames and parts thereof may be provided with any suitable braces or stays of wire or the like as good workmanship may suggest and as proper reinforcement of parts may require.

Such wires and braces are omitted for the

most part from the present invention and would confuse rather than aid in the clear presentation of the invention. It may be added, however, that the bowed cross parts b of said side frames preferably are made of bamboo of the requisite size, say two inches in cross section. The said side frames are connected by rigid rods or bars 5 front and rear at their top and other similar cross-bars, rods or the like 6 somewhat below the middle of said frames in this instance, and the joints or connections between all the parts of said main frame wherever they occur are made rigid and firm by clamps consisting of two parts 7. These parts are each bent between their ends to lap closely upon the corresponding portion of the frame and there are two clamping members on each side of each joint at right angles to each other which are united in this instance by means of screws but may be riveted together. This double clamping of said parts together where they cross as seen in Fig. 3 makes an exceedingly strong and firm connection. All or substantially all the crossings of parts of the main frame throughout the structure are provided with clips or clamps 7 as shown especially in Fig. 3, and the inside clamps on both side frames are alike provided with rigid lateral projections 8, Fig. 6, which serve as pivots for the corresponding planes P and P' at both edges thereof.

It is seen that the present structure belongs to what is commonly known as a bi-plane, but with this important difference as compared with such machines as heretofore made that it really contains four different planes, two on each side, but arranged one above the other in pairs and in such relation that the effect and value of two continuous planes is obtained for all ordinary purposes. This is plainly seen in Fig. 1 where both the upper and the lower planes are in the same working plane horizontally and are designed to hold this related position in all direct flights. However, the total length of these planes from end to end necessarily is quite considerable and conditions are liable to arise in flight when safety as well as expediency require that one or the other of said pairs of blades should yield or tilt or make other accommodation for the moment or even longer. Thus, for example, a given plane or pair of planes might

strike an adverse air current which would not reach the other pair at all and which would unavoidably and possibly abruptly tilt the entire machine even to the danger point. But by my pivotal support of said planes, say a single pair of pivots 8 front and rear at the edge of each plane, the planes thus struck would at once relieve the possible strain and danger by tilting or 10 swinging more or less on their pivots in the direction induced by such unfavorable currents. Then the moment the danger or the untoward pressure has been passed the said planes would automatically swing back 15 to normal position and the danger would be avoided. To meet such a condition mechanically and to automatically right the planes afterward I provide each plane with a retracting spring 10 which is wound spirally about a cross rod between the side posts of the sides of the frame and fixed to 20 said rod at its middle while the ends of said spring have arms 14 connected by wires 15 with the edges of the planes, two such 25 wires for each plane. The said springs are designed to be strong enough to hold the planes to their work in horizontal position as shown, and only when extraordinary conditions strike a plane do said springs 30 yield, say in some such measure as shown in dotted lines, Fig. 4.

It should probably have been stated before that each plane has a rigid edge frame of its own and that said planes are connected in pairs at either side of the machine by rigid braces or connecting rods or bars 35 pivotally connected to the said planes at their ends. Each pair of planes has two sets of these connections near their respective ends, and it follows that the two planes in each pair must work in unison and be 40 mutually responsive under all conditions of operation whether one or both planes be subjected to an operating force or air current strong enough to affect its position, or, 45 in other words, to change its position from the normal horizontal plane to what is shown in dotted lines, Fig. 4, more or less. Of course the springs 10 will restore the 50 said planes to normal as soon as the abnormal conditions affecting them are relieved. Obviously in view of the total length of the two sets of planes taken together and their 55 comparatively wide area of action a wayward current of air may strike one set or pair and not reach the other at all, and by having automatic accommodation for said planes as just described, I provide against injury or accident to the machine besides 60 affording a construction that can be mechanically utilized for special reasons or purposes, such, for example, as making turns in changing the angle of flight. To this latter end, and in order that the operator 65 may directly enter into this otherwise

automatic action of the planes and directly counteract such action or induce a like movement purposely, or with such automatic action on one side produce a like position in the other planes I provide the 70 means shown, for example, in Fig. 5. Herein there are shown two pedal levers 18, say like those of a bicycle, mounted on a shaft or cross bar 19, which would otherwise serve as a foot rest, and connected by wires 75 20 over sheaves 21 with the rear edge of the lower plane of each pair. This mechanism gives the operator complete control of the planes within the limits of springs 10 and their plane connections, and the 80 strength of said springs is such that they afford all the resistance the operator ordinarily needs in the pedals 20 to make the pedals regular rests for his feet. The said pedal levers 18 project across shaft 19 85 and have the wires 20 connected at or near their ends on both sides of said shaft, or above and below the same. This or any other mechanism serving the same purpose 90 may be adopted, the idea in any event being to give the operator personal control of the position of the planes, it being understood, however, that they naturally hold to the horizontal position through the springs 10 and need no help to do this. 95

An operator's seat S is supported centrally and front of the machine on a special seat frame seen in Fig. 5 and comprising parallel seat supporting tubes or pipes 22 and which in turn are supported by brackets 100 23 from the main frame of the machine. Said bracket supports carry standards 24 at their front upon which are mounted rotatable hand levers 25 and 26 which come within 105 convenient reach of the operator's seat and are designed to control the tail 27 and rudder 28 of the machine. These two parts are operatively supported at a suitable distance to the rear of the machine to afford the desired balancing and steering effects 110 and are supported on suitable extensions from the main frame and a cross shaft 29 on said extension which carries the tail proper indicated by 27. The rudder 28 is pivotally mounted on shaft 29 and bifurcated to bring half thereof above and the other half below tail 27, the said tail thus splitting the rudder. The said rudder 28 is controlled by 115 the operator through lever 25 at his right and which is operatively connected with the rudder by means of wires or cables 30 over suitably disposed sheaves here and there and connected at their front ends with the opposite ends of arm 31 fixed centrally on standard 24 which, in this instance, is rotatable by hand lever 25. This or equivalent mechanism can be used for controlling the 120 said rudder. It may be observed, however, that the wires 30 are threaded through the seat supporting tubes 22 and extend thence 125 130

to the rear where they approach the rudder from opposite sides in the best way to effect its easy control.

The tail plane or member 27 has an independent control to give it more or less inclination either way in respect to a horizontal plane according to the elevation of flight desired at any time and by which elevation is determined and maintained. Said control is through the wires 33 extending rearwardly to connect with the top and bottom of the rudder at 35 to get the desired leverage on the said tail and connected at their front ends with the ends of cross lever 34 fixed on post 24 and rotatable therewith. Said wires 33 run back through the corresponding seat supporting tube 22 and thence to the rudder and tail as shown. It will be seen that the rudder has its pivot in or 20 upon cross shaft 29 back from its front end in the end of the central slot therein which divides it upon said tail or plane, but the said tail is engaged with shaft 29 at its front edge. Furthermore the tail is moved by the 25 wires 33 through the rudder as a lever. To this end the wires 33 are attached to the rudder upon the posts or projections 35 top and bottom on the opposite sides from shaft 29 and in such relation that a pull on either 30 wire will cause the tail to swing on its pivot 29 correspondingly and give the tail the desired tilt or dip as the flight may require. Both the tail and the rudder move together in this operation but the rudder has a separate operation from the tail on its individual pivot 36, see Fig. 8.

Propellers R are shown as disposed at the rear edges of the respective rigid sides of the main frame and are driven by engine E 40 on the main frame back of the operator or in any other suitable position.

It is to be specially observed that the planes P and P' are hinged or pivoted comparatively near their inner ends so that any 45 tilting of the same is from this point and is emphasized especially in the outer free ends. This of course is of material advantage in the operation of the machine because it gives

the maximum movement of the planes to their outer ends where it counts for most in 50 any event. As shown, approximately two-thirds of the area of each plane is at the outer side of pivot 8.

Suitable wheels (not shown) may also be used at the runners or skids, but this is obvious in view of the general practice. 55

Obviously this machine can be converted into a monoplane by omitting say the two lower planes.

What I claim is:

1. In a machine as described, a main frame having transverse bars at its sides, a set of planes disposed in the same horizontal plane and each of said planes pivotally mounted on one of said bars and extending inward 65 from its pivot substantially half way across said frame and adapted to tilt independently of the other plane, and means adapted to automatically restore said planes to normal position after tilting comprising a spring 70 for each plane having a substantially rigid projection and a connection between said projection and the edge of said plane.

2. In an aeroplane, a main frame having forwardly bowed sides and the ends thereof constituting the top and bottom side bars of said frame, a set of planes on each side in substantially the same horizontal relation to the machine and pivotally mounted on the said side bars respectively between their 75 ends and extending part way into said frame from each side, said planes independently pivoted and adapted to tilt, in combination with springs on said frame connected with each plane and adapted to hold the same 80 normally in horizontal working relations under a spring tension, and a cable connecting the ends of the said springs with the edge portion of said planes.

In testimony whereof I affix my signature 85 in the presence of two witnesses.

DAVID BLACK.
